(57) **CLAIM**

The ornamental design for a rear flare, as shown and described.

DESCRIPTION

FIG. 1 is a front perspective view of the present design. FIG. 2 is a rear perspective view of FIG. 1. FIG. 3 is a front elevational view of FIG. 1. FIG. 4 is a back elevational view of FIG. 1. FIG. 5 is a bottom elevational view of FIG. 1. FIG. 6 is a top elevational view of FIG. 1. FIG. 7 is a first side elevational view of FIG. 1; and, FIG. 8 is a second side elevational view of FIG. 1. Evenly spaced broken lines show portions of the rear flare that form no part of the claimed design.

1 Claim, 6 Drawing Sheets
